UNITED STATES PATENT OFFICE.

LESLIE C. WOOD, OF GREENSBORO, NORTH CAROLINA.

CIRCUIT CLOSER.

Application filed July 23, 1924. Serial No. 727,753.

This invention relates to automatic switches, an object being to provide a switch which may be automatically operated by closing an electric circuit for the purpose of controlling a separate circuit.

Another object of the invention is the provision of a switch of the above character which is simple in construction, reliable and efficient in use and in which provision is made 10 to overcome the sudden action of the core of a solenoid used to operate the switch.

With the above and other objects in view, the invention further includes the following 15 novel features and details of construction to be hereinafter more fully described, illustrated in the accompanying drawing and pointed out in the appended claim.

In the drawing:—

Figure 1 is an elevation illustrating the invention.

Figure 2 is a detail perspective view of the switch arm.

Referring to the drawing in detail wherein like characters of reference denote corresponding parts, the reference character 10 indicates a housing within which the switch is positioned. The switch includes a pivotally movable arm illustrated in Figure 2 of the drawing and this arm includes a sleeve 44 which is mounted upon a stud 45 carried by the housing. Extending from the hub or sleeve 44 is an arm 46 which has connected to its outer end through the medium of a spring 47, the core 32 of a solenoid 25. This 30 solenoid is adapted to be connected in circuit with a source of current through the medium of conductors A and A'.

The switch further includes an arm 31 which extends from the hub 44 and this arm normally engages a stop 48. Spaced from this stop and arranged in the path of movement of the arm 31 is a contact 31' which may be connected in an electric circuit by means of a conductor 30. The arm 31 thus operates 40 between the stop 49 and the contact 31' and its movement in opposite directions is thus limited.

Also extending from the hub or sleeve 44 is an arm 50 and connected to this arm is one end of a spring 49, the opposite end of the 50 spring being anchored as shown at 51. The spring 49 thus serves to yieldingly hold the arm 31 against the stop 48. A conductor 30^a is connected to the hub or sleeve 44 so that when the arm 31 engages the contact 31' a 55 circuit may be completed through the switch.

The spring 47 provides a flexible connection between the core of the solenoid and the switch arm 46 and permits proper relative movement between the switch arm 31 and the 60 core of the solenoid, the spring 49 acting to yieldingly hold the arm 31 against the stop 48.

The invention is susceptible of various changes in its form, proportions and minor details of construction and the right is herein 65 reserved to make such changes as properly fall within the scope of the appended claim.

Having described the invention what is claimed is:—

In a device of the character described, a 70 housing, a switch including a solenoid located in the housing, a stationary pivot stud adjacent the solenoid, a hub radially mounted upon the stud, a switch arm extending radially outward from the periphery of the hub, 75 a stationary contact and stop arranged in spaced relation and between which the outer end of the switch arm is disposed, oppositely disposed arms projecting from the said hub at right angles to the switch arm, a hook 80 formed at the end of one of the latter arms, yieldable connection between the core of the solenoid and the said arm, and means yieldably connected with the outer end of the other arm of the oppositely disposed arms, whereby 85 to normally maintain the outer end of the switch arm in engagement with the stop, the energizing of the solenoid causing the switch arm to be moved into engagement with the stop, the yieldable means between the core of 90 the solenoid and the arm acting as a cushion to the sudden movement of the solenoid.

In testimony whereof I affix my signature.
LESLIE C. WOOD.
